METHOD OF MAKING HOLLOW METAL BODIES

Henry J. Simoneau, North Attleboro, Mass.

Application November 9, 1951, Serial No. 255,703

4 Claims. (Cl. 29—148.4)

1

This invention relates to improvements in a metal hollow ball or bead finding for use in the jewelry and dress trade and a method of making the same.

Heretofore, attempts have been made to make a hollow metal bead free of any openings so as to prevent any leaking of liquid therein during the coloring operation thereof. Any coloring liquid which may have leaked into the interior of the bead may thereafter escape from the bead to stain or otherwise mar the finished article to which the bead is attached. A method of making these beads now practiced in the trade consists in drawing a sheet metal disc blank into cup shape and thereafter closing the open end by a heading operation to form the bead, these beads thereafter being placed in a rolling mill to smooth out any irregularity in the surface thereof. This method involves considerable waste of material in the blanking operation to produce the discs and when the material is a precious or semi-precious material, such waste becomes of considerable importance in the cost of manufacturing the beads. Further, many beads made by this method leak to produce the undesirable results above referred to.

The general object of this invention is to provide for making hollow metal beads free of any seams or openings in the walls thereof.

Another object of this invention is to provide for making a hollow metal bead from tubular material by compressing the stock at intervals into substantially solid form to provide a tight seal for the head.

A more specific object of this invention is to provide for making a hollow metal bead from tubular stock in which the stock will be progressively reduced into a plurality of connected beads with the meeting edges of the beads tightly closed by a solid neck to be thereafter separated into individual beads.

With these and other objects in view, the invention consists of certain novel features as will be more fully described and particularly pointed out in the appended claims.

In the accompanying drawings:

Figure 1 is an elevational view of a bead made according to this invention;

Figure 2 is a central sectional view of the bead shown in Figure 1;

Figure 3 is a sectional view of a length of tubular material employed for making the beads;

Figure 4 is a sectional view of a fragmental portion of a die with tubular material therebetween shown in the process of being reduced into bead form.

2

Figure 5 is an elevation showing a plurality of connected beads as formed by the die shown in Figure 4;

Figure 6 is a sectional view of a plurality of such beads as shown in Figure 5 on an enlarged scale;

Figure 7 is a sectional view of a single bead;

Figure 8 is a sectional view of a fragmental portion of a rolling mill showing a plurality of 10 separate beads being acted upon;

Figure 9 is a plan view of a portion of the die shown in Figure 4;

Figure 10 is a sectional view taken substantially along line 10—10 of Figure 4;

Figure 11 is a sectional view of a die for further operation upon the beads.

In carrying out my invention I employ metal tubular stock material in the form of a tube 15 of any desired length having relatively thin walls, 20 circular in cross section, and of a diameter substantially equal to the diameter of the beads to be formed thereon. The tube may be made of any suitable metal material which may be precious or semi-precious or base metal as the case may be. In the present instance, I pass the tube 15 through a reducing die 16 which may be of the progression type having a plurality of cavities 17 therein which act upon the tube 15 to reduce the same step by step into a series of 25 nearly spherical bodies 18 connected to each other by a narrow neck portion 19 (see Figures 5 and 6).

The die 16 comprises upper and lower sections 20 and 21 in the meeting surface of which there 30 is provided a plurality of depressions which when the die is in the closed relation form cavities 22, the edge portions of which act upon the tube to reduce the same into bead form, as above stated. Each cavity 22 is spaced from the other, and the portions of the die between each cavity forms an annulus 23 to form the said neck portions 19. The size of each annulus 23 from the entrance end 24 of the die to the opposite end thereof is progressively reduced in diameter so that the annulus 25 and 26 on either side of the 35 last cavity 22' are of diameters less than twice the thickness of the wall of the tube 15. Thus, the neck portions 19 are compressed in the final die operation on the beads 18 into a solid compact mass to tightly close the meeting edges of the said beads.

The formed beads 18 are next severed from each other such as by means of a saw 27. The neck portions 19 are made of a length substantially equal to the thickness of the said saw 27 50 so as to leave a minimum of excess stock 28

about the said meeting edges of the said beads. The separated beads 18 are now operated upon by a rolling mill generally indicated 29 which functions to roll out any slight irregularity in the surface of the bead 18.

Heretofore, in rolling out hollow beads, any slight protuberance on the surface of the bead such as is provided by the remaining neck portion 28 will be pushed inwardly and make a dimple in the surface of the bead. I have overcome this by making the cavities of the die 16 slightly oval in shape with the longer axis *a* thereof extending lengthwise of the die. The difference in length between the axis *a* and axis *b* of the nearly spherical cavities 22 may be found by trial; in a bead to finish $\frac{3}{2}$ in diameter, I have found that the longer axis *a* may be made 15 thousandths to 20 thousandths longer than the axis *b*; thus, the beads leave the die in a nearly spherical form with the longer axis thereof extending in the direction of the said meeting edges of the bead. Such a bead, I have found will roll out perfectly smooth and spherical with the said excess stock 28 flowing or otherwise absorbed in the walls of the bead as the axis *a* and *b* are equalized. There is, of course, no opening in such a bead, nor is a seam noticeable with the naked eye.

After the beads have been rolled out, as above described, the same may be finished in any usual manner. If desired, the bead may be pressed, as shown in Figure 11, into other than spherical shape as by way of example, in an oval shape 30.

It will be apparent that I have disclosed a method by which a hollow spherical object may be made free of any seams or openings into the cavity thereof, and which method provides for a considerable reduction in the amount of waste usual in the prior art methods of making such beads. It will further be apparent that I may make these beads of any desired sizes and that these beads may also be subsequently shaped to various non-spherical form, if desired.

I claim:

1. A method of making a hollow metal bead which consists in reducing a length of tubing at

intervals to provide a nearly spherical body with the portions of said tube adjacent to said body forming a solid mass of a diameter less than twice the thickness of the walls of the tubing to completely close said body, severing said solid mass closely adjacent to said body and thereafter rolling said body under pressure to flow the excess of said solid mass remaining on said body into the walls thereof.

10 2. A method of making hollow metal beads which consists in reducing a length of tubing at intervals to provide a plurality of spaced nearly spherical body portions, each with an axis corresponding to the axis of the tube longer than the axis at right angles thereto with the portion of said tubing between said bodies forming a solid mass of a diameter less than twice the thickness of the walls of the tubing to completely close said bodies at their axial ends, severing each solid mass closely adjacent to the bodies connected thereto and thereafter rolling said bodies under pressure to flow the excess of said solid mass portions remaining on said bodies into the walls thereof and said bodies into spherical form.

15 3. A method of making hollow metal bodies as set forth in claim 2 wherein the severing of the said solid mass portions is by means of a saw and the spacing between each body is made substantially equal to the thickness of the saw.

20 4. A method of making hollow metal bodies as set forth in claim 2, the additional step of shaping the spherical body after rolling into non-spherical form.
